WEFT CARRIER HOLDING DEVICE FOR STATIONARY MAGAZINES

Filed Aug. 3, 1923

UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-CARRIER-HOLDING DEVICE FOR STATIONARY MAGAZINES.

Application filed August 3, 1923. Serial No. 655,539.

To all whom it may concern:

Be it known that I, EPPA H. RYON, a citizen of the United States, residing at Waltham, in the county of Middlesex and State of Massachusetts, have invented a new and useful Weft Carrier Holding Device for Stationary Magazines, of which the following is a specification.

This invention relates to a weft carrier magazine of the stationary type in which the weft carriers are placed in a series of vertical compartments from which they are successively removed as required by the operation of the loom. The weft carriers in these vertical compartments are found capable of twisting or turning movements while in storage, frequently resulting in entangling the weft ends, with consequent breakage thereof upon transfer to the active shuttle.

In my prior Patent No. 1,467,653, issued Sept. 11, 1923, I have shown devices for yieldingly engaging the butts of the weft carriers to prevent such angular movement thereof and means for automatically withdrawing the holding device of a given compartment from operative position upon indication of weft exhaustion to be replenished from that particular compartment.

It is one object of my present invention to provide means for simultaneously withdrawing all of the holding devices from operative position when the operator desires to replenish the magazine compartments.

My invention further contemplates the provision of means for automatically restoring the holding devices to operative position after such withdrawal.

In the present embodiment of my invention I provide for the operation of the automatic restoring mechanism on the occasion of the next subsequent weft carrier transfer, thus insuring the return of the holding devices to operative position within a negligibly short period after the filling of the magazine.

My invention further relates to arrangements and combinations of parts which will be hereinafter described and more particularly pointed out in the appended claims.

A preferred form of the invention is shown in the drawings, in which—

Fig. 1 is a side elevation of a weft carrier magazine embodying my improvements;

Fig. 2 is a partial sectional plan view thereof, taken along the line 2—2 in Fig. 1;

Fig. 3 is a partial sectional front elevation, taken along the line 3—3 in Fig. 2;

Fig. 4 is a detail sectional view taken along the line 4—4 in Fig. 2; and

Fig. 5 is a perspective view of one of the holding devices.

Referring to the drawings, I have shown a weft carrier magazine of a usual commercial type and having a magazine frame 65 with ribs or projections 11 on its inner face, dividing the magazine into a series of vertical compartments 12 within which the weft carriers W are stored. I have also shown vertically moving release members or bars 13, locking plungers 14 for said bars, and lifting levers 15 (Fig. 3) mounted on a cross shaft 16 (Fig. 1) and adapted to selectively engage and move the bars 13. The shaft 16 is movable both axially and angularly to engage and lift a selected release member or bar 13, upon indication of exhaustion of a weft carrier corresponding to the compartment associated with said bar. 70

The bar 13, after being raised by its arm 15, is held in raised position by its plunger 14 until the indicated shuttle returns to transfer position. The bar 13 is then depressed by the action of an arm or plate 17 (Fig. 3) mounted on a shaft 18 connected for movement by actuating devices not shown. A shuttle feeler 20 is connected to the shaft 18 through an adjustable link 21 and an arm 22 (Fig. 2). For a more complete description of the construction and 80 operation of these usual parts of this type of weft carrier magazine, reference is made to my prior patent above mentioned.

For restraining or preventing turning movements of the weft carriers in the compartments 12, I provide each compartment with a vertically extended holding device 25 which, in its preferred form, comprises a blade or plate slidably mounted in slotted guiding projections 26 and each having cam 90 95 100

portions 27 and 28 which engage projections 31 and 32 on the magazine frame as the blade or device moves down, such movement being assisted by a spring 30 for each blade. 5 Each device 25 is provided with an outwardly projecting portion 33 (Fig. 5) having an offset flange or lug 34 at the lower end thereof. The lugs 34 are positioned for engagement by the upper ends of the 10 release bars 13 as they move upwardly to release the weft carriers upon indication of weft exhaustion and by such engagement each device 25 is withdrawn from operative position as a corresponding weft carrier is 15 released.

My present invention relates particularly to the provision of a slide 40 mounted on the frame 10 and having a plurality of V-shaped notches or cam surfaces 41 formed in the 20 upper edge thereof. The plate 40 is preferably secured in position by caps or cover plates 42 at the ends thereof and by a screw 43 extending through a slot 44 near the center thereof. The slide 40 is also bent at 25 right angles at 45 to provide a convenient handle and the opposite end is of semi-circular form as indicated at 46. The normal running position of the slide is at the extreme right or front of its path of travel, 30 as indicated in Fig. 1, with the notches 41 permitting free downward movement of the devices 25.

When the operator desires to replenish the magazine, the slide 40 is pushed rearward or to the left thus simultaneously raising and holding the devices 25 by the action of the cam surfaces 41. All of the devices 25 are thus held in withdrawn position while the magazine is being filled by the operator. 40 Having completed the filling of the magazine, the operator is presumed to restore the slide to the position shown in Fig. 1, thus releasing the devices 25 to engage the weft carriers.

45 In the event that the operator occasionally forgets to restore the slide 40 to inoperative position, I have provided an arm 50 secured to the end of the shaft 18 and having an offset end 51 with upper and lower cam surfaces. As the arm 50 is moved downward and thereafter upward at the transfer of the next succeeding weft carrier, one of the cam surfaces on the end 51 will engage the rounded end portion 46 of the slide 40, restoring it to its normal inoperative or forward position.

50 I have thus provided for simultaneous removal of all of the devices 25 from operative position when desired by the operator and I have also provided for the automatic return of the devices 25 to operative position not later than the next succeeding weft carrier transfer. The period of time commonly intervening is so short that entangle-

ment of the weft ends cannot reasonably 65 occur.

Having thus described my invention and the advantages thereof, I do not wish to be limited to the details herein disclosed otherwise than as set forth in the claims but 70 what I claim is:—

1. In a loom, in combination, a stationary magazine having a plurality of vertical weft carrier compartments, devices to prevent angular movement of the weft carriers in said 75 compartments, and means to render all of said devices simultaneously inoperative.

2. In a loom, in combination, a stationary magazine having a plurality of vertical weft carrier compartments, devices to prevent angular movement of the weft carriers in said 80 compartments, means to render said devices simultaneously inoperative, and means to restore all of said devices to operative position. 85

3. In a loom, in combination, a stationary magazine having a plurality of vertical weft carrier compartments, devices to prevent angular movement of the weft carriers in said 90 compartments, manual means to render said devices inoperative, and automatic means to restore said devices to operative position.

4. In a loom, in combination, a stationary magazine having a plurality of vertical weft carrier compartments, devices to prevent angular movement of the weft carriers in said 95 compartments, means to render all of said devices simultaneously inoperative, and automatic means to simultaneously restore said devices to operative position. 100

5. In a loom, in combination, a stationary magazine having a plurality of vertical weft carrier compartments, devices to prevent angular movement of the weft carriers in said 105 compartments, means to render all of said devices simultaneously inoperative, and means to restore said devices to operative position, said latter means becoming operative upon the next succeeding weft carrier transfer. 110

6. In a loom, in combination, a stationary magazine having a plurality of vertical weft carrier compartments, devices to prevent angular movement of the weft carriers in said 115 compartments, a manually operated slide having a cam action on each device to remove said devices from operative position when moved in one direction, and automatic means to move said slide in the opposite direction to restore said devices to operative 120 position.

7. In a loom, in combination, a stationary magazine having a plurality of vertical weft carrier compartments, holding devices to prevent angular movement of the weft carriers in said compartments, means to render all of said devices simultaneously inoperative, a shuttle feeler, means to actuate said 125

feeler upon weft carrier transfer, and a device connected to move with said shuttle feeler and effective to restore said holding devices to operative position.

8. In a loom, in combination, a magazine having a plurality of vertical weft carrier compartments, actuating mechanism for said magazine, devices to prevent angular move-

ment of the weft carriers in said compartments, and means operable independently of the magazine actuating mechanism and effective to render said devices simultaneously inoperative.

In testimony whereof I have hereunto affixed my signature.

EPPA H. RYON.
